Divided and this application July 28, 1958, Serial No.
51,975

Claims priority, application Italy February 16, 1957

Term of patent 14 years

(Cl. D70—1)

FIG 1

FIG 2

FIG 3

FIG 4

Figure 1 is a front perspective view of a sewing machine showing my new design;

Figure 2 is a rear perspective view showing a side of the machine;

Figure 3 is a top plan view; and

Figure 4 is a top perspective view showing the other side of the machine from that shown in Figure 2.

This application is a division of my application Serial No. D. 47,336, filed August 12, 1957, now Design Patent D. 184,556, dated March 10, 1959, and entitled Sewing Machine.

I claim:

The ornamental design for a sewing machine, as shown and described.
